SCOTT M. ABBOTT, OF WATERTOWN, MINNESOTA.

PUMP-ROD COUPLING.

SPECIFICATION forming part of Letters Patent No. 737,191, dated August 25, 1903.

Application filed June 5, 1903. Serial No. 160,164. (No model.)

To all whom it may concern:

Be it known that I, SCOTT M. ABBOTT, a citizen of the United States, residing at Watertown, in the county of Carver, State of Minnesota, have invented certain new and useful Improvements in Pump-Rod Couplings, of which the following is a specification, reference being had therein to the accompanying drawings, in which—

Figure 1 is a side elevation; Fig. 2, a horizontal sectional view taken on the line 2 2 of Fig. 1 through the coupling means; Fig. 3, a vertical sectional view taken on the line 3 3 of Fig. 2; Fig. 4, a vertical sectional view taken on the line 4 4 of Fig. 2; Fig. 5, a horizontal sectional view taken on the line 5 5 of Fig. 1; Fig. 6, a similar view taken on the line 6 6 of Fig. 1, and Fig. 7 a similar view showing a slightly-varied form of the connection between the pump-handle and handle-coupling rod.

The main object of this invention is to provide a coupling by which the piston-rod of a pump may be alternately connected to the pumping-rod of a windmill and to the handle of the pump by merely shifting the position of a coupling-lever.

A further object of the invention is to connect rigidly to the pump piston-rod a coupling-head and to mount on this head a simple mechanism which may be operated to alternately connect the piston-rod with the windmill pumping-rod and with the pump-handle.

35 A further object of the invention is to interpose in the windmill pump-rod a relief-spring to take up the sudden jars and strains occasioned by quickly connecting the pump-rod to the piston-rod.

40 Other and equally important objects and advantages will appear hereinafter.

Referring to the various parts by numerals, 1 designates the pump, 2 the bifurcated standard, which carries at its upper end the guide 3 for the pump piston-rod 4. To this piston-rod, above the bifurcated standard and the guide 3, is rigidly bolted the coupling-head 5. This head is formed with the vertical groove 6, in which lies the piston-rod, and through 45 the piston-rod and the coupling-head is passed the bolt 7, the piston-rod being clamped between the cap-like washer 8 and the coupling-

head. The coupling-head is provided near its right-hand end with a vertical passage 9 and the upward-extending coincident sleeve 55 10 for the passage of the windmill pump-rod 11. This sleeve 10 is preferably formed integral with the coupling-head; but of course it may be secured to said head in any suitable way. Near its left-hand end the head is formed 60 with the vertical passage 12 to receive the handle-coupling rod 13. Extending outward horizontally from each end of the coupling-head is a small tube 14, each of which receives and guides a coupling-pin 15, the outer 65 end of these pins being turned down and each pivotally connected to the adjacent end of the shifting-rod 16. This shifting-rod is held in place at the side of the coupling-head by means of a retaining-plate 17, whose arms extend downward and outward in opposite directions, their lower ends being bent inward to form the supports 18 for the shifting-bar 16, the inner edges of said supports fitting closely against the under side of the coupling-head, 70 75 as clearly shown in Figs. 3 and 4. On the side of the coupling-head, at each end thereof just above the shifting-rod 16, are formed outward-extending guide-lugs 5^a, which serve to hold the shifting-rod down on the supports 80 85 18. Surrounding the bolt 7, between the retaining-plate or washer 17 and the face of the coupling-head, is a sleeve 19, on which is journaled the coupling-lever 20, the washer 17 serving to retain the lever in position. The lower end of this lever is formed with the gear-teeth 21, which intermesh with the rack 22, formed on the upper edge of the shifting-bar 16, so that by throwing the coupling-lever toward the left side, as shown in Figs. 1 and 2, 90 95 the shifting-bar 16 will be moved toward the right and one coupling-pin 15 will be moved inward to engage a perforation in the handle-coupling rod 13, and the other coupling-pin 15 will be disengaged from the pumping-rod 11 of the windmill. By shifting the coupling-lever to the right the movements of these parts will be reversed and the windmill pumping-rod 11 will be engaged by one of the coupling-pins and the coupling-rod 13 will be released. 100

The pump-handle 23 is connected to the standard by means of the link 24, and the upper end of the handle is bifurcated, as at 25, and straddles the piston-rod of the pump.

Connected to the bifurcated upper end of the handle is the lower end of the handle-coupling rod 13. The lower end of the handle-coupling rod is enlarged and extends inward 5 toward the pump-rod, this inward-extending part forming a support for a wearing-shoe 26, said shoe being provided with flanges at its upper and lower edges to engage the enlargement of the handle-coupling rod. This wearing-shoe 10 rests against the piston-rod, so that when the piston-rod is connected to the windmill pump-rod the wear will be on the shoe instead of on the coupling-rod. This shoe or its equivalent is very desirable even when the 15 handle-coupling rod is connected to the pump piston-rod in order that there shall be no bending or springing of the coupling-rod during the movement of the handle and to make the connection between the pump-handle and 20 the piston-rod as nearly rigid as possible. To each side of the handle-coupling rod, at its lower end, is bolted a forward-extending jaw 27, which is provided on its inner face with an inward-extending cylindric lug 28, said 25 lugs fitting in corresponding perforations in the arms of the bifurcated end of the handle 25. The ends of these jaws are connected together by a transverse bar 29 above the handle 25 and opposite the wearing-shoe, said 30 bar lying close to the edge of the piston-rod 4. The object of this bar is to prevent the handle-coupling rod being moved forward when the pump-handle is lifted, said bar contacting with the edge of the piston-rod and 35 preventing any forward movement of the handle-coupling rod. One jaw of the coupling-rod may be formed integral with the main part of said rod and the other jaw bolted thereto if considered desirable.

40 In Fig. 7 the lower end of the handle-coupling rod is secured between the outer ends of two jaws 30, the inner ends of which are pivotally connected to the upper bifurcated end of the handle. Mounted in these jaws and 45 bearing on the piston-rod is a wearing-wheel 31. This wheel serves the same purpose as the wearing-shoe shown in Figs. 1 and 6 and may or may not be used, as desired.

Through the upper end of the handle-coupling rod is passed a short pin 32, which will 50 prevent said rod passing downward entirely through the coupling-head.

The windmill pump-rod is formed in two sections 11^a and 11^b, the lower one of which, 55 11^a, fits and slides in the sleeve 10 of the coupling-head. The upper end of this section 11^a is bent horizontally to form the lip 33, and said horizontal portion is apertured for the passage of the vertical bolt 34, which extends upward 60 from said horizontal portion. The lower end of the portion 11^b is extended horizontally to form the lip 35, which lies over the lip 33, and is also apertured for the passage of the bolt 34. Surrounding this bolt, its lower end resting 65 on the lip 35, is a strong coil relief-spring 36, and on the upper end of this bolt is screwed a nut 37, which retains a plate 38 in

position and is adapted to compress the spring 36. The operation of this portion of the invention is obvious. When the coupling-pins 70 15 are shifted by means of the lever 20 to quickly connect the windmill pump-rod to the piston-rod 4 during the reciprocation of the windmill pump-rod, the sudden jar will be taken up by the relief-spring and the pump 75 will be relieved thereby of the sudden strain. By adjusting the nut 37 the tension of the spring 36 may be so regulated that the lips 33 and 35 will remain in contact with each other during the ordinary operation of the pump by 80 the windmill, the spring yielding only when there is a sudden and unusual strain exerted by the windmill pump-rod. This relief-spring is very necessary when it is desired to connect the reciprocating windmill-rod with the coupling-head. Without it the sudden jar of 85 quickly shifting the coupling-pin 15 into engagement with the part 11^a is apt to disarrange the apparatus and to bring an unnecessary strain on it.

90 It will thus be seen that I provide a coupling means which is simple in construction and which by the mere shifting of a lever will disconnect the piston-rod of the pump from the pump-handle and connect it to the 95 pumping-rod of the windmill during the reciprocation of the windmill pumping-rod without causing any undue sudden jar or strain on the coupling means. The coupling mechanism is simple, is not liable to get out 100 of order, and the wear thereon will be exceedingly small, so that the mechanism will last for a long time and require little or no repairs.

Having thus described my invention, what I claim as new, and desire to secure by Letters 105 Patent, is—

1. In a coupling for pump-rods, the combination of a coupling-head, means for securing said head to the piston-rod of a pump, a passage through said head for the windmill pump-rod, a second passage therethrough for the handle-coupling rod, a pair of pins carried by the coupling-head and adapted to pass across the 110 passages therein, a shifting-bar connected to said pins, and means for reciprocating said 115 shifting-bar whereby the coupling-head may be connected and disconnected from the windmill pumping-rod or the handle-coupling rod.

2. In a coupling for pump-rods, the combination of a coupling-head, means for securing 120 said head to the piston-rod of a pump, a vertical passage through said head for the windmill-rod, a second passage through said head for the handle-coupling rod, a pin adapted to extend across each of said passages, a shifting-rod 125 connected to the outer ends of said pins, a coupling-lever pivoted on the coupling-head and adapted to reciprocate the shifting-rod.

3. In a coupling for pump-rods, the combination of a coupling-head, means for rigidly 130 securing said head to the piston-rod of a pump, a vertical passage through said head near one of its ends to receive the windmill pumping-

- rod, a similar passage near the other end of said head to receive a handle-coupling rod, a pin carried by the head at each of its ends and adapted to extend inward across the adjacent 5 passage through said head, a shifting-bar, the outer ends of the pins being connected to said bar, an operating-lever provided with teeth on its lower end and adapted to engage a rack formed on the upper edge of the shifting-bar, 10 and a retaining and supporting plate carried by the head and adapted to form a support for the shifting-bar.
4. In a coupling for pump-rods, the combination of a coupling-head, means for securing 15 said head to the piston-rod of a pump, a passage therethrough to receive the windmill-rod, a second passage through said head, a handle-coupling rod extending through said passage, a coupling-pin carried by said head 20 and adapted to extend inward and to enter a perforation in the handle-coupling rod, a second pin adapted to extend inward through a perforation in the windmill-rod, a shifting-bar connected at its ends to the outer ends of the 25 sliding pins, and means for reciprocating said bar in either direction, and means for pivotally connecting the lower end of the handle-coupling rod to the upper end of the pump-handle.
5. In a coupling for pump-rods, the combination of a coupling-head, means for securing said head to the piston-rod of a pump, a passage therethrough to receive the windmill coupling-rod, a second passage through said 30 head, a handle-coupling rod extending through said second passage, a coupling-pin carried by said head and adapted to extend inward and to enter the perforation in the handle-coupling rod, a second pin adapted to 35 extend inward through a perforation in the windmill-rod, a shifting-bar connected at its ends to the outer ends of the coupling-pins, means for reciprocating said bar in either direction, means for pivotally connecting the 40 lower end of the handle-coupling rod to the pump-handle and a pair of guides carried by the handle-coupling rod and adapted to engage the front and rear edges of the pump piston-rod to prevent any material forward or 45 50 rearward movement of the handle-coupling rod during the movement of the pump-handle.
6. In a coupling for pump-rods the combination, of a coupling-head, means for securing said head to the piston-rod of a pump, a 55 passage through said head for the windmill pump-rod, a second passage therethrough for the handle-coupling rod, a pair of pins carried by the coupling-head and adapted to pass across the passages therein, a shifting-bar 60 connected to said pins, means for reciprocating

ing said shifting-bar whereby the coupling-head may be connected and disconnected from the windmill pumping-rod or the handle-coupling rod, a two-part windmill pumping-rod, one of said parts extending through the 65 coupling-head, the other part being connected to the first part above the coupling-head, and a relief-spring interposed between the two parts of the windmill pump-rod, whereby the coupling-head may be connected to the windmill pump-rod during the reciprocation of said rod, and the relief-spring will take up the sudden strain caused thereby.

7. In a coupling for pump-rods the combination, of a coupling-head, means for securing 75 said head to a pump piston-rod, a passage therethrough for the windmill pumping-rod, a second passage therethrough for a handle-coupling rod, a coupling-lever pivoted on the coupling-head, means operated by said lever 80 for connecting the coupling-head to the windmill pumping-rod, and disconnecting it from the handle-coupling rod or vice versa, a handle-coupling rod, a wearing-shoe carried by 85 said rod at its lower end and adapted to bear on the forward edge of the pump piston-rod, a pair of jaws connected to said handle-coupling rod at its lower end and extending rearward therefrom on each side of the piston-rod, a wearing-pin connecting the rear ends 90 of said jaws and lying close to the forward edge of the piston-rod, and a pump-handle pivotally connected to said jaws.

8. In a coupling for pump-rods, the combination of a coupling-head, means for securing 95 said head to the piston-rod of a pump, a vertical passage through said head for the windmill pump-rod, a second passage through said head for the handle-coupling rod, a pin adapted to extend across each of said 100 passages, a shifting-rod connected to the outer ends of said pins, a coupling-lever pivoted on the coupling-head and adapted to reciprocate the shifting-rod, a two-part windmill pumping-rod, one of said parts extending through 105 the coupling-head the other part being connected to the first part above the coupling-head, and a relief-spring interposed between the two parts of the windmill pump-rod whereby the coupling-head may be connected 110 to the windmill pump-rod during the reciprocation of said rod and the relief-spring will take up the sudden strain caused thereby.

In testimony whereof I hereunto affix my signature, in the presence of two witnesses, this 1st day of June, 1903.

SCOTT M. ABBOTT.
